UNITED STATES PATENT OFFICE.

KNOX TAYLOR, OF HIGH BRIDGE, NEW JERSEY, ASSIGNOR TO TAYLOR-WHARTON IRON AND STEEL COMPANY, OF HIGH BRIDGE, NEW JERSEY, A CORPORATION OF NEW JERSEY.

TAMPING TOOL.

Application filed August 3, 1921. Serial No. 489,653.

To all whom it may concern:

Be it known that I, KNOX TAYLOR, a citizen of the United States, residing at High Bridge, in the county of Hunterdon and 5 State of New Jersey, have invented certain new and useful Improvements in Tamping Tools, of which the following is a specification.

Tamping tools now in use are generally 10 unsatisfactory in that they wear rapidly in service and tend to part the ballast material or force their way through the same instead of holding and driving it to place.

It is therefore the object of my invention 15 to provide a tamping tool whereof at least the wearing portion of the head shall be constructed of manganese steel, which is remarkable for its toughness, hardness and enduring qualities. In practicing the invention, the head, or its wearing or impact portion, may be integral with the remaining structure, or it may be detachable, or detachable and reversible. Moreover, it is otherwise so constructed that it may be readily 20 cleared of any ballast material which it may trap, and re-dressed, as by grinding, if necessary or desirable.

The nature, characteristic features, and scope of the invention, will more readily be 25 understood from the following description and claims, reference being had to the accompanying drawing, forming a part thereof, wherein—

Fig. 1 is a perspective view of the tamping tool embodying my invention.

Fig. 2 is a section on line 2—2 of Fig. 1.

Fig. 3 is a side elevation of a modification.

Figs. 4 and 5, respectively, are sectional and bottom views of the tamping tool shown 40 in Fig. 3.

Fig. 6 is a sectional view of a detachable wearing or impact element.

Fig. 7 is a perspective view of a detachable and reversible wearing or impact element.

Fig. 8 is a side elevation of a further modification.

Fig. 9 is an end view thereof; and—

Fig. 10 is a similar view of the same re-dressed after service.

Referring to Figs. 1 and 2, a tamping tool is indicated, the head 5 of which is preferably constructed of manganese steel. The impact portion of the head is cupped or 55 concaved, as at 6, to facilitate grinding, when necessary, but mainly to engage the ballast material. There are end slots 7 and laterally opening slots 8, which when present are useful in ejecting any ballast material which may stick in the cupped portion 6.

In the modification, Figs. 3 to 5, the impact or wearing portion of the head is cupped as at 9, the cupped area merging 65 with a relatively deep slot 10 extending the length of the head and open at both ends. Aside from its utility in ejecting trapped ballast material, the full length slot 10 is useful to temporarily take care of metal 70 peened from the surface, and it is further useful in that it simplifies redressing of the impact surfaces as by grinding or otherwise.

The head may be solid with the shaft, or it may be constructed with a detachable 75 wearing or impact element 11, having an interlocking fit such as shown, for example at 12.

I may also, if desired, provide a reversible impact element such as, for example, shown 80 in Fig. 7, which illustrates a double member so constructed and arranged that when one face 13 is worn, it may be reversed to present the other face.

Figs. 8, 9, and 10 illustrate a tamping head having a full length slot 14 which extends to within a comparatively short distance of the shaft, and is cupped as at 15. In service, the wing members or side walls 16, have a tendency to spread, as indicated in 90 dotted lines in Fig. 10.

The head is then re-dressed, as by grinding, so as to insure uniformly straight outer walls. The effect of the spreading is to impart a flare 17 to the slot as clearly shown 95 in Fig. 10 and this condition is manifestly

useful in holding and advancing the ballast material.

Having described my invention, I claim:—

1. A tamping tool including the combination with a head, of an impact element having an interlocking fit therewith, said impact element being formed of manganese steel and having a cupped working face and a slot communicating therewith.

2. A tamping tool whereof the head is 10 constructed of manganese steel with a deep slot ranging lengthwise thereof defining wings which spread in service and impart a flare to the slot.

In testimony whereof I affix my signature. 15

KNOX TAYLOR.
